UNITED STATES PATENT OFFICE.

DAVID EDWARDS, OF CARDIFF, COUNTY OF GLAMORGAN, WALES.

LIFT OR HOIST OR OTHER ELEVATOR.

SPECIFICATION forming part of Letters Patent No. 249,325, dated November 8, 1881.

Application filed September 27, 1881. (No model.) Patented in England March 1, 1881.

To all whom it may concern:

Be it known that I, DAVID EDWARDS, a subject of the Queen of Great Britain, residing at Cardiff, in the county of Glamorgan, Wales, carpenter, have invented certain new and useful Improvements in Lifts or Hoists and other Elevators, (for which I have received Letters Patent in England No. 869, dated 1st March, 1881,) of which the following is a specification.

10 My invention consists of the improvements, hereinafter described and illustrated in the accompanying drawings, in lifts or hoists and other elevators, by which improvements the mechanism is simplified, and lifts or hoists or elevators produced in which the load is automatically suspended at any height to which it may have been raised and readily lowered to any extent by giving motion to the winding-shaft in a direction contrary to that by which 15 20 the raising is effected, the load being automatically suspended in any position to which it may have been lowered on ceasing to give a backward motion to the shaft.

I will describe and illustrate my improvements in connection with a lift.

Figure 1 represents in side elevation, Fig. 2 in end elevation, and Fig. 3 in plan, a hand-worked lift constructed according to my invention. Fig. 4 represents a longitudinal section 30 of the clutch mechanism of the lift, drawn to a larger scale.

The same letters indicate the same parts in Figs. 1, 2, 3, and 4.

a is the principal shaft of the lift, and *b* is the counter-shaft. The said principal shaft *a* is capable of a rotatory motion in its bearings, and carries at one end a pulley or wheel, *c*, over which an endless hand-worked rope or chain passes. By means of this rope or chain 35 40 45 and pulley the lift is worked, as hereinafter described. On the shaft *a* is a tube or sleeve, (marked *d* and *e*,) the said sleeve being capable of rotating freely on the said shaft. The part *d* of the sleeve carries a ratchet-wheel, *f*, with which the pawl *g*, turning on the counter-shaft *b*, engages. The other part, *e*, of the rotating sleeve *d* *e* consists of a flanged drum, and constitutes two clutches, the acting faces of which 50 may either be conical or plain, as represented in the sectional view, Fig. 4.

h *i* are two disks, situated respectively on op-

posite sides of the flanged drum or double clutch *e*, the acting faces of which clutch *e* may either be conical when the acting faces of the disks *h* *i* are conical, or plain, as represented in the drawings. The disk *i* is fixed to the shaft *a* by a key and the screw-pin *k*. The disk *i* is the only part of the clutch mechanism which is permanently fixed to the shaft *a*. The other disk, *h*, forms part of a sleeve, *h*², which sleeve 55 60 65 70 75 80 85 90 95 100 *h*² is capable of turning and sliding upon the first-described or principal sleeve *d*. The second sleeve, *h*², has a pinion, *h*³, upon it, with which the toothed wheel *l* on the counter-shaft *b* gears. (See Figs. 2 and 3.) The said counter-shaft *b* carries the pulley or wheel *m*, over which the raising rope or chain is coiled for supporting the load to be raised; but the second sleeve, *h*², in small lifts may constitute the winding-drum on which the raising chain or rope is coiled. The two disks *h* *i*, on opposite sides of the drum *e*, are connected together by the rigid links *p* *p*, secured to the said disks in the manner represented in Fig. 4. When the links *p* *p* are parallel to the shaft *a* the disks *h* *i* are at the greatest distance apart, and do not grip between them the flanged drum *e*, and the shaft *a* turns without the sleeve *d*, drum *e*, and ratchet-wheel *f*. When, however, the links *p* *p* take an oblique position the two disks *h* *i* are drawn together, and they grip between them the flanged drum *e*, and all the parts of the clutch mechanism are geared together—that is to say, the sleeve *d*, drum *e*, and the second sleeve, *h*², and its disk *h* move with the shaft *a*, to which the other disk, *i*, is fixed.

When the shaft *a* is turned in the proper direction by means of the endless rope of the pulley *c* to raise the load the resistance of the load, transmitted through the shaft *b*, toothed wheel *l*, pinion *h*³, and sleeve *h*², to the disk *h*, causes the links *p* *p* to take a position oblique to the shaft *a*, thereby sliding the sleeve *h*² on the sleeve *d* and causing the flanged drum *e* of the said sleeve *d* to be gripped between the two disks *h* and *i*. The result of the sliding of the sleeve *h*² is the gearing of the parts *d* *e* *f* to the shaft *a*, the whole of the parts of the gearing now moving together, so that by the turning of the shaft *a* by the endless band and pulley *c* the motion of the said shaft is transmitted through the sleeve *d*, pinion *h*³, and

toothed wheel l to the counter-shaft b , on which the pulley m , carrying the load, is fixed, and the load is raised, the pawl g and ratchet wheel f preventing the backward motion of the shaft 5 so long as the parts are geared together, and the raised load is retained in whatever position it may have been brought to.

In order to lower the load, the shaft a is turned in the backward direction. This motion allows the second sleeve, h^2 , to slide toward the ratchet-wheel f by bringing the links $p p$ nearer to parallelism with the shaft. The two clutch-disks $h i$ are thereby slackened on the drum e , and the sleeve h^2 is free to take a backward motion. The said sleeve h^2 is thereby ungreased from the shaft a , and is free to rotate in a backward direction on the principal sleeve d , so as to permit the load on the pulley m to descend, the descent continuing only so long 15 as the backward motion of the shaft a is continued. Thus the load is automatically suspended at any height to which it may have been raised, and readily lowered to any extent by giving motion to the winding-shaft b 20 in a direction contrary to that by which the raising is effected, as described.

The disks $h i$ and drum e may be covered by the sheet-metal casing q when the lift is exposed to the weather; but the said casing may 30 be omitted.

Instead of the rigid links $p p$, chain or other flexible links may be employed with the same effect.

In order to cause the weight, as in cage- 35 hoists, to descend, should the empty cage not be sufficiently heavy to overcome the friction of the gearing, I combine with the clutch-disks $h i$ of the gearing two stops, the said stops having for their object to effect the backward 40 or descending rotation of the disk h when the links $p p$ have come into their parallel position. These stops are indicated in dotted lines in the sectional plan, Fig. 4, and in plan in Fig. 4^A, and elevation in Fig. 4^B, in combination 45 with the two clutch-disks h and i . The stop on the clutch-disk h is marked x , and the stop on the clutch-disk i is marked y . The ends of these stops overlap one another, as represented. When the load is being lifted 50 the said stops $x y$ separate; but in the descending rotation of the said disks $h i$ the said stops come in contact, as best seen in the plan in Fig. 4^A, and the two disks are made to rotate together, the links $p p$ being thus prevented by the said stops $x y$ from taking an oblique position in the return or back rotation 55 of the disks $h i$.

I make the pawl g , which gears with the ratchet-wheel f , fixed on the loose sleeve d in 60 the manner illustrated in Fig. 4^C. The eye or bush g^2 of the pawl g turns upon the counter-shaft b . On the said shaft b are two collars, $g^3 g^4$. Between one side of the eye g^2 and the fixed collar g^4 is a coiled spring, g^5 , which presses 65 the eye of the pawl forcibly against the collar g^3 . g^6 , Fig. 3, is a stop for limiting the rising motion of the pawl g . On lifting the load the

rotation of the shaft b in the lifting direction causes sufficient friction between the eye of the pawl g and collar g^3 to lift the said pawl 70 from its ratchet-wheel f , so that during the raising of the load the pawl does not slip over the teeth of the ratchet-wheel f . On the shaft b coming to rest a slight reversal of its motion takes place, and the pawl g , engaging with the 75 ratchet-wheel f , prevents the back motion of the sleeve d , as before described.

An ordinary pawl may be used instead of the noiseless pawl represented.

Fig. 5 represents in longitudinal section, 80 and Fig. 6 in side elevation, mechanism constructed according to my invention provided with a single clutch.

a is the shaft of the lift.

i is the conical disk, free to rotate on the shaft a , having in this arrangement the ratchet-wheel i^2 attached to it for the pawl on the counter-shaft to engage with.

r is a sliding and rotating sleeve, which is geared by the pinion r^2 to the counter-shaft. 90

s is a disk fixed to or made in one piece with the sleeve r . On the said sleeve r is a hollow conical collar, r^3 , which engages with the conical disk i .

Opposite the disk s is a second disk, t , fixed by a key to the shaft and rotating with it, its position on the shaft being adjusted and fixed by the lock-nuts at u . Between the two disks $s t$ is a coiled spring, v , by which they are pressed apart. The two disks $s t$ are connected together by the rigid links $w w$, having spherical ends, which seat themselves in properly-shaped seats in the disks $s t$. The links $w w$ are not arranged parallel to the shaft a , but are inclined thereto, as best seen in Fig. 6. 105 When the shaft a is turned for raising the load, the rotation of the disk t making the links $w w$ approach parallelism, the disk s and sleeve r are made by the thrusting action of the said links to cause the clutch-disk r^3 to press against and grip the conical disk i , so as to gear the sleeve r and its disk s with the shaft a , and effect the raising of the load through the pinion r^2 and gearing connected therewith. 110

The application of my improvements to elevators other than lifts differs in no essential respect from its application to a lift as hereinbefore described and illustrated. 115

When the lift, hoist, or elevator is to be worked by steam or other motive power the hand-pulley c and its endless band are replaced by toothed or other gearing. 120

Having now described my said invention and the manner of carrying the same into effect, what I claim is—

1. The combination of a clutch-disk fixed on the main shaft, a second clutch-disk connected therewith by rigid or flexible links, and a loose sleeve also mounted upon said shaft, and which constitutes the winding-drum, or through which the winding-drum is worked, substantially as described. 125

2. The combination, with the coupled clutch-disks upon the main shaft, of stops which en-

gage upon the reversal of said shaft, substantially as and for the purpose set forth.

3. The combination, with the clutch mechanism and ratchet-wheel mounted upon the main shaft, of an automatic and silent pawl, as described, mounted on the counter-shaft, substantially as set forth.

4. The combination, with the clutch-disks, of links connecting said disks, as described, 10 and by means of which they may be caused to approach or recede from each other, substantially as and for the purpose described.

5. The combination, with a clutch device

and means, as described, for operating the same, of a loose disk or sleeve having a surface for 15 engagement with said clutch, a ratchet-wheel connected with or carried by said disk or sleeve, and a pawl operating in connection with said ratchet, as set forth.
